UNITED STATES PATENT OFFICE.

CHARLES A. WESTERVELT AND JAMES P. WALTERS, OF UHRICHSVILLE, OHIO.

SELF-OILING JOURNAL-BOX.

SPECIFICATION forming part of Letters Patent No. 596,671, dated January 4, 1898.

Application filed June 21, 1897. Serial No. 641,584. (No model.)

To all whom it may concern:

Be it known that we, CHARLES A. WESTERVELT and JAMES P. WALTERS, citizens of the United States of America, and residents of 5 Uhrichsville, Tuscarawas county, in the State of Ohio, have invented a new and useful Improvement in Self-Oiling Journal-Boxes, of which the following is a specification.

The invention relates to self-oiling journal-boxes for railway rolling-stock and is additional to our improvement in car-axle lubricators patented January 15, 1895, United States Letters Patent No. 532,618.

The present invention consists in certain 15 novel combinations of parts, hereinafter set forth and claimed, whereby the axle spindle or journal is adapted to carry a simple and effective revolving oil-elevator and is at the same time provided with a lateral controller 20 which is direct and positive in its action and is readily adjusted or renewed should the lateral play become too great. The end bearing so formed is kept thoroughly lubricated. The device is adapted to axles of standard length, 25 and the end bearing is rendered non-rotary and readily renewable in a novel manner.

A sheet of drawings accompanies this specification as part thereof.

Figure 1 of the drawings represents a vertical longitudinal section through an improved self-oiling journal-box, showing the journal, oil-elevator, and lateral controller in elevation. Fig. 2 represents a horizontal section on the line $z-z$, Fig. 1. Fig. 3 represents an 35 elevation of the end piece of the journal detached, showing its inner end with the oil-elevator in place thereon. Fig. 4 is an elevation of the end bearing detached, showing its outer end.

40 Like letters and numerals refer to like parts in all the figures.

In common with the self-oiling journal-box set forth in our previous specification, forming part of said Letters Patent No. 532,618, 45 this improved journal-box comprises a shell-body A, which is conveniently a single casting, the customary brass B above the journal of any known or improved construction, a spring-supported oil-holding "cellar" C in 50 contact with the journal at bottom, a centrifugal oil-elevator D, revolving with the journal

E within a housing preferably integral with said shell-body A, and a face-plate or end plate F and lid G, closing the outer end of the box, said housing of the revolving oil-elevator D forming at bottom an oil-chamber a, Fig. 1, and provided at its sides with open-topped oil-pockets b, into which the oil is directly thrown by said oil-elevator and from which it flows through centripetal passages c 60 into the open top of said cellar C.

The shell-body A, brass B, cellar C, and lid G, together with the cellar-supporting spring H, form no part of the present invention and will not, therefore, be more particularly de- 65 scribed.

The revolving oil-elevator D is preferably and conveniently formed by uniting two flat strips of spring-steel by means of a pair of bolts d and springing them apart at mid-length to embrace an end piece I, with which the journal E of the improved bearing is provided. The flat outer end of this end piece contacts directly with the inner surface of a non-rotary end bearing J, supported centrally by the end plate F, which is reinforced, as represented at 1 and 2 in Figs. 1 and 2, with reference to this function, said reinforced end plate, said non-rotary end bearing, and said end piece constituting together 70 a "lateral controller" for determining the lateral movement of the truck relative to the axle.

The oil-elevator D keeps the end bearing 75 thoroughly lubricated by the oil which re-flows down its respective blades as they revolve in the upper part of the housing. The oil-elevator is held between a beveled circumferential flange 3 on the end piece I and the end of the journal E, the bevel of said flange 80 directing the oil to the face of the end bearing J and serving also to facilitate springing the oil-elevator into place. For attaching the end piece I the journal E is provided with a central longitudinal end bore 4, Fig. 2, and 95 the end piece is constructed with a stem 5, which is keyed fast within said end bore by a pin 6, Fig. 2.

The end bearing J, being preferably of brass, is renewably attached to the end plate 100 F and rendered non-rotary in the following manner: A central square socket 7 in the in-

ner surface of the end plate is occupied by a square boss 8 on the back of the end bearing, and a central bolt 9, having its head held in like manner within a square socket 10 in the 5 inner face of the end bearing, extends outward through bolt-holes 11 and 12 in the end bearing and end plate, respectively, and is provided with a screw-nut 13 at its outer end.

Having thus described said improvement, 10 we claim as our invention and desire to patent under this specification—

1. An improved self-oiling journal-box, for railway rolling-stock, comprising a reinforced end plate, a non-rotary end bearing supported by said end plate in line with the journal, an end piece carried by the journal to contact with said end bearing, and a revolving oil-elevator carried by said end piece and serving to lubricate said end bearing, substantially as hereinbefore specified.

2. The combination, in a self-oiling journal-box for railway rolling-stock, of a reinforced end plate, a non-rotary end bearing supported by said end plate, an end piece carried by the journal and constructed with a beveled circumferential flange, and a revolving oil-elevator embracing said end piece be-

tween said flange and the end of the journal, substantially as hereinbefore specified.

3. The combination, in a self-oiling journal-box for railway rolling-stock, of a journal having a central longitudinal end recess, an end piece having a stem keyed fast within said end recess, a revolving oil-elevator carried by said end piece, an end bearing co-acting with said end piece, and an end plate supporting said end bearing, substantially as hereinbefore specified.

4. The combination, in a self-oiling journal-box for railway rolling-stock, of a reinforced end plate provided internally with a central square socket and having a central bolt-hole, a non-rotary end bearing having a boss fitted to said socket and provided with a central recess and bolt-hole, and an axial 45 bolt having its head seated in the recess last named, substantially as hereinbefore specified.
